UNITED STATES PATENT OFFICE.

WILLIAM THOMAS TATE, OF BUXTON, IOWA.

CAR-FENDER.

1,079,194.

Specification of Letters Patent.

Patented Nov. 18, 1913.

Application filed April 23, 1910. Serial No. 557,264.

To all whom it may concern:

Be it known that I, WILLIAM T. TATE, a citizen of the United States of America, residing at Buxton, in the county of Monroe and State of Iowa, have invented new and useful Improvements in Car-Fenders, of which the following is a specification.

This invention relates to car fenders and particularly to an attachment thereon which consists of one or more movable retainers or arms and means at the front of the fender designed so that when an object is struck by the fender the arms will be released and automatically moved to positions at the front of the object to prevent such object from being accidentally thrown off the fender.

In the drawings forming a portion of this specification and in which like numerals of reference indicate similar parts in the several views, Figure 1 is a front elevation of my improved fender looking in the direction of the arrow shown in Fig. 4, and showing the fender in its tripped position. Fig. 2 is a side elevation thereof, shown in its normal position. Fig. 3 is a top plan view showing the movable member at the front of the fender moved to a position to release the retaining arms. Fig. 4 is a side elevation showing the said movable member moved to a position to release the arms. Fig. 5 is a detail perspective view of a portion of one of the arms and a portion of the fender showing the arm in full lines in its normal position, and the dotted lines indicating its tripped position.

The fender proper as shown at A, may be of any well known construction, but as illustrated, it consists of a platform B which receives the rear extremities of the scoop forming arms C. Any well known means may be provided for attaching the fender to the car. These arms are extended downwardly, as shown at D, and adjacent to their forward ends they are offset and seated in a transverse groove E in the platform. The forward extremities of the said arms are curved outwardly and then downwardly and secured in any well known manner to the front edge of the platform.

A movable actuating member is located at the front of the platform, and as illustrated, the said member consists of a frame A' formed to provide a tripping bar or front cross bar 1, side bars 2 and a rear cross bar 3, the side bars being slidably mounted in

suitable guides 4 which depend from the platform of the fender. The platform is formed at its sides to provide notches 5 which form stop shoulders 6 and 7 to limit the forward and rearward movements of the frame. Movable retaining members 8 are pivoted in the fixed bearings or journals 14 on the platform, and as shown, their rear ends are formed to provide short arms 9 which receive the rear terminals of springs 10. These springs are coiled about portions of the said retaining members and their forward terminals are suitably secured to the platform of the fender. The retaining members are formed at their forward ends to provide arms 11 which extend normally in vertical positions. Each retaining member is formed to provide a depending finger 12 which extends into the notch at the side 75 of the platform. The fingers 12 of the said retaining members are normally engaged by locking elements or fingers 13 on the hereinbefore described movable frame. The fingers 13 may be moved forwardly and 80 rearwardly in the notches at the sides of the platform and when at their forward limit of their movements they are disposed directly opposite the fingers 12 of the retaining members to hold the retaining members 85 against rotating through the action of the springs 10. The front bar 1 of the actuating member A' is normally disposed slightly in advance of the front edge of the fender and it is arranged in a position with respect 90 thereto to be engaged by the object struck by the fender so that sliding movement in a rearward direction will be imparted to the frame causing the fingers 13 of the frame to be moved to their released positions and 95 entirely out of engagement with the finger 12 on the retaining members. Immediately upon movement of the frame as just described the retaining members will be moved automatically through the action of the 100 springs 10 so as to cause their arm portions to assume horizontal positions at the front of the fender and to be arranged with respect to the fender so as to hold the object caught thereby against becoming accidentally thrown off. The arms at the front ends of the retaining members are curved, as shown, so as to lie slightly above the plane of the lower forward edge portions of the arms 1 of the fender.

The construction of the fender herein described and shown is extremely simple.

In operation should a person be struck by the fender the arms will be instantly moved to positions to prevent the person from being thrown off while the car is in motion. While I have described the sliding frame beneath the platform of the fender as a means for holding the arms against the tension of the springs of said arms it will of course be understood that any well known actuating element may be employed in lieu thereof.

I claim.

1. A car fender having a movable member at the front thereof, a rotatably mounted retaining member, and means on the movable member for engaging the said retaining member to hold the same normally against rotation.

2. A fender for vehicles having a transversely extending movable member at its forward edge, revolvably mounted retaining elements having vertically disposed arms at their forward ends, spring means exerting its tension against the elements to cause the same to revolve in one direction, the said arms being located at the forward end of the fender, and means on the movable member for engaging the said elements to hold the same against rotation against the tension of the spring means and operable upon movement of the said movable member to release the said elements to cause the same to move through the tension of the spring and to cause the arm of the said retaining member

to assume a horizontal position at the front 35 of the fender.

3. A fender for vehicles having movable spring-controlled retaining arms located at the forward end of the fender, and movable actuating means operable to hold the arms 40 normally in vertical positions and operable when moved in one direction to release the arms.

4. In a car fender, the combination with a scoop; of a sliding frame at the side of the scoop, the said frame being provided with a front portion which is normally spaced from the front of the scoop, retaining elements rotatably mounted at the sides of the scoop and provided at their forward ends 50 with normally vertically disposed fingers, fingers on the sliding frame engaging the first fingers to hold the retaining elements normally against rotation, and springs exerting their tension against the retaining elements to rotate them in one direction when the fingers of the sliding frame are released from the fingers of the retaining elements so as to cause the retaining elements to move to positions where their fingers will be disposed substantially in a plane with each other and horizontally.

In testimony whereof I affix my signature in presence of two witnesses.

WILLIAM THOMAS TATE.
